UNITED STATES PATENT OFFICE.

JEANNETTE B. MARCH, OF BALTIMORE, MARYLAND.

PORTABLE WINDOW-BALCONY FOR FLOWERS.

SPECIFICATION forming part of Letters Patent No. 443,369, dated December 23, 1890.

Application filed April 11, 1890. Serial No. 347,427. (No model.)

To all whom it may concern:

Be it known that I, JEANNETTE B. MARCH, of Baltimore, in the State of Maryland, have invented certain new and useful Improvements in Portable Window-Balconies for Flowers; and I do hereby declare the following to be a full, clear, and exact description of the invention, such as will enable others skilled in the art to which it pertains to make and use it, reference being had to the accompanying drawings, which form part of this specification.

My invention relates to an improvement in a portable window-balcony for flowers; and it consists in the combination and arrangement of parts, which will be fully described hereinafter.

The object of my invention is to provide a portable folding flower-balcony for windows, and which is designed to be secured to the building outside of the window to receive pots of flowers and vines, and which is so constructed as to be adapted to windows with or without shutters.

Figure 1 is a plan view of a balcony which embodies my invention. Fig. 2 is a front elevation of the same. Fig. 3 is an end view of the balcony, the window-sill and the supporting parts of the balcony, which are secured thereto, being also shown in section. Fig. 4 is a detached view of the eyebolts to which the brackets are pivotally connected.

A represents a suitable metallic frame, which may be made rounding or angular, and to which the other parts of the balcony are to be attached in any suitable manner. The vertical end piece B and the front piece B' will be made of any suitable material, and are pivoted at the points V to the corners of the frame A, so that they can be swung down, as shown in dotted lines in Figs. 2 and 3. These vertical pieces B B' are made separate from each other and are held in a vertical position by means of suitable catches e. These sides and ends may be given any ornamental appearance that may be desired and will be made to conform to the shape of the frame A, to which they are attached.

Detachably fastened to the frame A by means of suitable holding devices a of any kind is the bottom C, which is preferably pro-

vided with a number of rings x to receive the saucers in which the flower-pots are to be placed, and which pots will preferably be large enough to have their upper edges extend about on a level with the top edges of the end and front pieces B, so that these parts will not in any way obstruct the view of the growing plants. The saucers in which the pots are placed may be made of iron, earthenware, or any other suitable material. Secured to the under side of this bottom C is a suitable guide G, of any suitable construction, and in which the inner end of a sliding plate or support H is made to catch. This support H has its outer ends turned upward and inward, so as to extend over the top of the wooden part of the window-sill, so as to receive a screw, nail, or other fastening device. For the purpose of forming a secure fastening for the inner end of this slide H there is to be inserted into the window-sill a screw-socket I, which is provided with a perforated flange at its upper edge, and through this flange fastening-screws are to be passed. The inner perforated portion of the slide H extends over the top of this metallic socket I, and a screw J, having a handle upon its upper end or a means of any kind attached to it for the purpose of enabling it to be turned readily, is used, and this screw J is passed through the inner corner of the slide H into the socket I, as shown.

In order to enable the slide H to be more securely attached to the metallic socket I, a flange is struck down from the slide where the perforation is made through it for the screw to pass through, and this flange fits inside of the upper end of the socket and thus assists in securing the slide in position. This metallic socket and its screw J afford a much stronger and safer fastening for the inner end of the slide H, which has to support the greater part of the weight of the balcony, than would be furnished by any ordinary screw or nail.

In order to hold the slide H rigidly in position, there are formed both through the slide and the guide through which it moves slots L, and through these slots a clamping device of any kind is passed, so that after the slide has once been adjusted upon the sill it can be securely clamped in position.

The brackets P are secured to the outer side

of the window-sill by means of the headed 5
nails W, which pass through the openings X
and into slots extending upward from the said
openings and which are smaller than the
heads of the nails. Upon the upper ends of
these brackets are formed headed revolving
catches a, which pass through suitable open-
ings made in the frame A, and by means of
which the frame and the brackets can be fast-
ened together securely. By turning the heads
10 of the catches in a line with the openings b,
through which they pass, the brackets can be
moved downward until the heads of the nails
W are within the openings X, when they can
be removed.

When this balcony is to be used upon a
house where there are shutters and it is de-
sired at any time to close the shutters, the
flower-pots must be removed and the bottom
20 Clifted out. The end and front pieces are then
unfastened at their upper corners and allowed
to hang downward, as shown by dotted lines
in Figs. 2 and 3, the balcony offering no ob-
struction whatever to the opening and closing
25 of the shutters. The screw-socket I, being
adapted to be sunk into the window-frame so
as to be just flush therewith, forms an invis-
ible screw-holder and prevents any obstruc-
tion from being formed upon the window-
30 frame.

Having thus described my invention, I
claim—

1. In a flower-balcony, the combination, 35
with the horizontal frame having transverse
perforations, of eyebolts which have their
straight portions passed through the perfora-
tions and secured therein and a bracket hav-
ing a horizontal upper portion which is hinged
in the eye of the bolt, substantially as de-
scribed.

2. The combination of the bottom of the
balcony with the guide G, which is secured to
its under side and provided with a slot, the
slide H, which moves in the guide and has its
inner end shaped so as to extend over the 45
lower edge of the window-guide, and brackets
for supporting the balcony, substantially as
specified.

3. The combination, with the bottom of the
balcony, having a guide, of a slide which 50
moves in the guide, having its inner end bent
to extend over the window-sill, the metallic
socket in the window-sill, the screw which
passes through the bent end of the slide, and
the brackets for supporting the balcony, sub- 55
stantially as described.

In testimony whereof I affix my signature in
presence of two witnesses.

JEANNETTE B. MARCH.
